delphia, Pa., a corporation of Delaware

Application May 14, 1936, Serial No. 79,808

7 Claims. (Cl. 179—171)

This invention relates to the control of the gain or amplification of variable gain amplifiers and, more particularly, to a novel gain control device by means of which an input signal may be amplified to an extent which is governed by a second electrical signal. The invention is capable of general application and may be used in any instance where it is desired to control the amplification of a signal in the manner above mentioned. For example, the invention is well adapted for use in television systems, and finds several different applications therein. In order to illustrate the invention, a specific example of its use for one particular purpose in a television system will be given. It will be understood, of course, that specific embodiments of the invention other than those disclosed herein may be used and are, therefore, to be considered within the scope of the invention.

One object of the invention is to provide a variable gain amplifier, whose gain may be controlled by an electrical signal while preventing such control signal from appearing in the output circuit of the device.

Another object of the invention is to provide a variable gain device, whose gain may be controlled without the introduction of a transient voltage or other extraneous voltage in the output circuit of the device, as the gain thereof is varied.

Another object of the invention is to provide an amplifier having a high impedance input circuit, which when energized by two input signals, will form in its output circuit, an output signal proportional to the difference between the input signals.

Still another object of the invention is to provide an amplifier having one input circuit which may be adapted for push-pull input signals, and another input circuit for a control signal, the amplifier being so arranged that, first, the control signal is definitely established in such a manner as to control the mutual conductance and thus the gain of the amplifier tubes without introducing degeneration of the input signals and second, the output signal of the amplifier comprises only the input signal amplified by an amount dependent upon the control signal.

A still further object of the invention is to provide a multi-branch variable gain amplifier having means for balancing the delay or phase shift of the several branches, so as to provide a uniform frequency characteristic for the device.

Other objects and features of the invention

will appear hereinafter as the description proceeds.

In the accompanying drawings:

Fig. 1 is a circuit diagram of a device employing the basic principles of the invention; 5

Fig. 2 shows the characteristic curves of certain tubes which may be used in the device of the invention;

Fig. 3 is a schematic illustration of a scanning signal generator employing an embodiment of the invention which may be used to actuate the scanning means in a conventional television system; and 10

Fig. 4 is a circuit diagram illustrating a modification of the invention. 15

The general principles of the invention may be understood from a consideration of Fig. 1 wherein the output signal E_0 appearing in the output circuit corresponds to the amplified input signal E_1 , the degree of amplification depending upon a second or auxiliary input signal E_2 . The input stage of the device comprises two tubes V_1 and V_2 , which tubes have their cathodes connected in a common cathode circuit including the resistor R_1 . Tubes V_1 and V_2 are preferably identical, one with the other, with respect to their electrical characteristics. The average bias voltages applied to the grids of these tubes are maintained at corresponding values with respect to some predetermined voltage level, such as ground, by means of the bias battery C and the grid-leak resistor R . Due to this resistor, the voltage of the grid of tube V_1 fluctuates about the predetermined bias voltage level in response to the signal E_1 , whereas the grid of tube V_2 is maintained at the bias voltage level, since the signal E_1 is not applied to the grid of tube V_2 . The cathodes of tubes V_1 and V_2 are maintained at some voltage greater than ground potential, depending upon the voltage drop across the resistance R_1 . Thus, the input signal for tube V_2 comprises the bias voltage due to battery C and the voltage drop in the resistor R_1 , while the input signal for the tube V_1 comprises the same voltages plus the alternating component of the signal E_1 , which causes the grid voltage of tube V_1 to fluctuate about the mean value of the grid voltage of tube V_2 . 30

A portion of the output signal from tube V_1 is taken across a variable resistance R_2 in the anode circuit of the tube and is transferred to an additional tube V_3 by a conventional resistance-capacitance coupling circuit. Output signals from tubes V_2 and V_3 are added together and the com- 35 40 45 50 55

bined output signal is taken across a common resistance R_3 connected in the anode circuits of these tubes. The resistance R_2 may be so adjusted that the amplification of any input signal 5 through the branch comprising tubes V_1 and V_3 is the same as the amplification of any input signal through the other branch comprising tube V_2 alone. It will be noted, however, that the phase of the signal transferred through the first 10 branch will be opposite to the phase of the signal transferred through the second branch. In other words, due to the additional tube V_3 in the first branch, there will be a shift or difference in phase of 180° between the signals transferred 15 through the two branches. Consequently, any input signal or voltage variation introduced in both tubes V_1 and V_2 , which signal might, for example, be one introduced across the resistor R_1 , will cancel in the output circuit. That is to say, 20 the amplified signal from tubes V_1 and V_3 appearing across resistance R_3 will be of equal amplitude and opposite phase with respect to the corresponding signal transferred through the branch comprising tube V_2 , and the two signals 25 will thus cancel each other. It will be seen, however, that any signal introduced in one of the branches but not in the other branch will be transferred and will appear in the output circuit. Likewise two signals of opposite phase applied 30 to the input circuits of tubes V_1 and V_2 would add together in the output circuit. Thus an input signal of opposite phase with respect to signal E_1 might be applied to tube V_2 and would produce a signal E_0 in the output circuit similar 35 to the output signal obtained by applying the signal E_1 to tube V_1 .

As noted above, the A. C. components of the input signal E_1 are applied only to tube V_1 , and the biasing voltages for the grids of tubes V_1 40 and V_2 are identical. Consequently, the signal E_1 will be transferred through the system, but variations in the bias voltage of the tubes, which will appear as input signals of the same phase to both tubes, will cancel in the output circuit. 45 **Tubes V_1 and V_2 may have the characteristic that their mutual conductance, which is a measure of gain or amplification, is a function of the input voltage.** The amplification of the system may then be varied by varying the voltage drop across 50 the resistance R_1 which will vary the mutual conductance of tubes V_1 and V_2 and, consequently, will vary the degree of amplification of the signal E_1 which, as above pointed out, may be transferred through the branch comprising tubes V_1 55 and V_3 . The voltage drop across the resistance R_1 may be conveniently controlled by means of an additional tube V_4 whose cathode is connected in common with the cathodes of tubes V_1 and V_2 and whose anode is connected to the plate supply 60 source B. Thus, the current drain of tube V_4 , which may be used to control the voltage drop across the resistance R_1 , may be varied readily by varying the input signal E_2 applied to the tube. It will be seen, therefore, that the input 65 signal E_1 may be amplified in the device by an amount dependent upon a second or auxiliary input signal E_2 to obtain an output signal E_0 similar in wave shape to the input signal E_1 and containing no components directly proportional to 70 the auxiliary signal E_2 .

As will be apparent from considering Fig. 1, the resistance R_1 is included in both the input and output circuits of tubes V_1 , V_2 and V_4 , and the voltage thereacross is included in the total 75

voltage in the input circuits of these tubes as well as in the output circuits of tubes V_1 and V_2 , and in addition this voltage may constitute the total output voltage of tube V_4 . The total input signal voltage of tube V_1 may comprise the voltage across R_1 plus an input signal E_1 , and that of V_2 may comprise only the voltage across R_1 or if desired another input signal similar to E_1 but opposite in phase may be added to the voltage of R_1 (see Fig. 4). Preferably, the signals in the output circuits of V_1 and V_2 , which are combined to produce the desired difference or output signal, may comprise the total output signals less the voltage across R_1 , although the total output signals might be used. 15

In the preferred mode of operation of the device, the signal E_1 will be small as compared with the signal E_2 . Further, in general, the combined space current of tubes V_1 and V_2 will be of the same order as that of tube V_4 . The cathode drive of tube V_4 which biases tubes V_1 and V_2 may then offer certain unusual advantages. It will be seen that when a signal is applied to the input circuit of tube V_4 , the tube will tend to draw enough current so that the voltage across R_1 is the same as the impressed voltage. Under these conditions, the actual grid-to-cathode or tube input voltage would be simply the bias voltage. The tube will not, in general, however, draw sufficient current to bring about this condition, but will fail by the differential grid voltage required to cause the change in space current. In other words, the tube is not actuated by the input voltage but by the difference between that voltage and the voltage obtained across the resistor R_1 . By designing the circuit so that a small change in actual grid voltage of tube V_4 will cause a large change in the voltage drop across the resistor R_1 due to the change in space current of tube V_4 , the actual voltage across R_1 may be made to follow the input voltage E_2 very closely. 30

It will be observed that the operating range of input voltages may be considerably larger than the total rated grid swing of the tube V_4 , since 45 the actual grid-to-cathode voltage is the difference between the voltage E_2 and the voltage drop across the resistor R_1 , neglecting, of course, the unidirectional component which may be controlled by the average bias on the grid of tube V_4 . Thus, for example, the actual grid-to-cathode voltage on tube V_4 may be a small fraction, say $\frac{1}{2}$, of the actual input voltage. Since the circuit 50 may be designed so that the tube operates over only part of its grid voltage-plate current characteristic, signal distortion due to non-uniformity of tube characteristic may be minimized to a considerable extent. 55

It is worthy of note that degeneration of the signal E_1 , which is usually present when an appreciable impedance is introduced in the cathode circuit of a vacuum tube amplifier having an anode load circuit, is avoided due to the property of this circuit of balancing out signals introduced in both branches. It should be noted further that the effect of variations in space current of tubes V_1 and V_2 , which variations are small, is further materially reduced by the use of the cathode load for tube V_4 . Since this tube is actuated by the difference in voltage between the input signal E_2 70 and the voltage drop across the resistor R_1 , which difference voltage will be small, it makes little difference whether the latter voltage is due to space current in tube V_4 or to some other cause, and in any event, the tube V_4 will operate to mini- 75

5 mize the discrepancy in voltage between signal E_2 and the resistor voltage. Thus, the circuit of tube V_4 not only establishes the bias on tubes V_1 and V_2 in accordance with the signal E_2 , but it also functions to minimize any tendency of these tubes to have any other bias, and thus minimizes any degeneration of the signal E_1 due to the cathode resistor R_1 .

10 In order to obtain full advantage of the cathode load feature of the invention, it is desirable that tubes V_1 and V_2 have an appreciable load in their respective anode circuits. In the circuit of Fig. 1, the anode circuits of tubes V_1 and V_2 are loaded to different extents, the loading of tube V_2 being 15 less than that of tube V_1 , due to the operation of tube V_3 which tends to reduce the effective impedance of R_3 . In Fig. 4, there is shown a modification of the invention which provides for loading to the full extent. As before, it is desirable to 20 obtain in an output circuit the difference between the output signals of tubes V_1 and V_2 . In the circuit of Fig. 4, tubes V_1 and V_2 , constituting one group, are supplied with load impedances R_3 and R_4 , respectively, which are of suitable magnitudes 25 to act as proper loads for their respective tubes. The amplified signals obtained across R_3 and R_4 are supplied through blocking condensers to the grids of tubes V_5 and V_6 , constituting another group. The cathode of tube V_5 may be connected 30 to the plate of tube V_6 , the anode of tube V_5 may be connected to the B supply, and the cathode of tube V_6 may be connected to ground. If desired, the plate voltages of tubes V_5 and V_6 may be increased by connecting the cathode of tube V_6 to the negative side of a second B voltage supply 35 unit whose positive side is connected to ground. The common junction of the tubes V_5 and V_6 is connected to an output load resistance R_5 which may be connected to an intermediate point on the 40 whole B voltage supply. Obviously, this intermediate point might alternatively be provided by a drop wire or other similar device. Tubes V_5 and V_6 should preferably have identical electrical characteristics, and their respective input 45 grids may be suitably biased to similar operating points by the grid-leak resistors R_6 and R_7 , as shown.

50 Tubes V_5 and V_6 are thus connected so that their output circuits are in series with each other and the battery B. The output circuit for the group, however, is the resistance R_5 which for A. C. components is effectively connected across each tube output circuit. Signals across R_4 are supplied to the input circuit of tube V_6 while signals across R_3 are combined with the output voltage across R_5 and then supplied to the input 55 circuit of tube V_5 .

By this interconnection of input and output 60 circuits, a circuit is obtained such that the output signal is proportional to the difference between the input signals, and yet the system is perfectly stable.

65 This result is due to the fact that as far as results are concerned the output circuit has the properties of a cathode load output circuit, but the circuit interconnections are such that signals introduced in one input circuit are transferred without any phase reversal, while signals in the other circuit are transferred reversed 70 in phase. Thus signals supplied to the input circuit of tube V_6 are reversed in phase and transferred to the output circuit from which they are fed back to the input of tube V_5 which tube operates to control the amplitude of the output signal 75 so that it will be the same as that due to an input

signal supplied to tube V_5 which signal, however, would be transferred to the output circuit without reversal of its phase. Thus the output signal will be proportional to the difference between the input signals. For example, in the case in which the same signal is applied in each input circuit, the current in each tube would change by the same amount and there would be no current change in R_5 since the current through this impedance is the difference between the current in each tube. Whereas, if equal and opposite signals were applied to each input circuit, the current in one tube would increase while that of the other would decrease, the difference current through R_5 would produce an output signal which would feed back affecting the grid voltage of the one tube and the plate voltage of both in such a way as to cause equal amplification of both input signals. The resultant output signal would then be proportional to twice the input signal. 20

25 Consider now the operation of the circuit of Fig. 4 as a whole. The group of tubes V_1 and V_2 may be biased to the same point by means of the common resistance R and the common voltage across R_1 . A signal E_1 may be combined with the voltage across R_1 and supplied to tube V_1 . If desired, a voltage of opposite phase with respect to E_1 may be similarly introduced in the input circuit of the tube V_2 by the push-pull input circuit shown. Output signals from tubes V_1 30 and V_2 may be derived from resistances R_3 and R_4 respectively and supplied to the group of tubes V_5 and V_6 . It will be noted that both tubes V_1 and V_2 have appreciable impedances in their output circuits in addition to the resistance R_1 and 35 therefore the voltage across R_1 will be substantially independent of tubes V_1 and V_2 and determined only by the control signal E_2 . The grid-to-cathode voltage of tube V_6 will correspond to the voltage across R_4 while that of tube V_5 will 40 be the voltage across R_3 combined with that across R_5 .

45 Preferably R_3 and R_4 should have the same value, and V_5 and V_6 should be similar tubes. Under these conditions, the output signal across R_5 will be proportional to the difference signals supplied to the group of tubes V_1 and V_2 , and the proportionality factor will be dependent upon the control signal E_2 which will not otherwise appear in the output circuit. The input circuits of tubes 50 V_5 and V_6 constitute high impedance sources and consequently do not tend to restrict the use of proper load impedances R_3 and R_4 in the output circuits of tubes V_1 and V_2 . Hence, the optimum 55 operating conditions for the circuit as a whole may be obtained.

Thus, as before, an input signal E_1 is supplied to one of two amplifying branches each of which includes an amplifier tube whose mutual conductance is a function of its grid voltage. If desired, a similar signal of opposite phase may be supplied to the input circuit of the other branch. A second input signal is supplied to the input circuits of both branches in such a way that the mutual conductance of an amplifier tube in 65 each branch is modified, producing in each branch an identical undesired signal and determining the degree of amplification of the signal E_1 . The output of each of these branches is then combined in a circuit which forms in its 70 output circuit a signal proportional to the difference between the two input signals, that is, a signal corresponding to E_1 but amplified by an amount determined by E_2 , and which permits the use of load impedances in the anode circuits of 75

the input tubes, thus enabling better control of the gain of these tubes by the control tube.

The amplifier shown in Fig. 1, and described above, is adaptable for use over a wide frequency range due to the fact that, in general, resistance-capacitance coupling is used and, as well known, such coupling devices are substantially uniform over a frequency range extending from some low value to reasonably high values. For use in television system, however, where extremely wide frequency ranges are encountered, certain features are desirable, as will now be described.

To obtain uniform amplification over the video-frequency range, which may extend upward to two or three magacycles in a high definition television system, it is preferable to add a small amount of inductance to the load resistance of each video-frequency stage in order to minimize the effect of the capacity to ground of the coupling condenser and the inter-electrode capacity of the amplifier tube. Such inductances are shown at L and L_1 in Fig. 1.

Referring to Fig. 1 for the moment and considering the operation of the device, it will be seen that with the inductances present, the frequency characteristics of the two branches are not similar and, consequently, in order to balance out very high frequency components introduced in both branches, it is necessary to modify the high frequency response of one branch, for example, the branch including tube V_2 , to make the frequency response of that branch conform to the frequency response of the other branch; or, alternatively, it is necessary to take precautions to prevent the introduction of such high frequency components in the circuit itself. Where such high frequency components are outside the range of frequencies which it is desired to transmit, but may be included in the several input signals, it is preferable to remove the said components at the point of introduction to the circuit. Where it is desirable to transmit the said components, the frequency characteristic of the circuit may be corrected, for example, by inserting a very small inductance L_2 in the plate circuit of tube V_2 . By proper adjustment of the inductances L , L_1 and L_2 , uniform frequency characteristics may be obtained for the two branches. It will be noted that the correction must include not only the effect of inductances added to overcome specific frequency response defects, but also the inductances due to the physical length of the connections themselves which are of importance at the high television modulation frequencies.

It is likewise important that the frequency response of each branch be the same at the low frequency as well as the high frequency end, and hence in Fig. 4 the values of the condensers and resistors connected to R_3 and R_4 should be so designed that the transfer circuits will have similar frequency characteristics. As R_3 and R_4 should preferably be equal, this may easily be accomplished by using condensers and grid leak resistors of equal values.

It is worthy of note that in the circuits of Figs. 1 and 4, no unusual restrictions are placed upon the source of B voltage for the circuits, and the same B supply as that used for associated apparatus may be employed. In addition, one side of each of the several input and output circuits may be grounded for A. C. components which facilitates the use of the circuit. Furthermore, the use of transformers which would tend to restrict the operable frequency range of the circuit is avoided

except for the input of Fig. 4 which might be obtained from any vacuum tube phase inversion circuit, thus completely avoiding the use of transformers.

The variable gain amplifier provided by the invention finds several uses in television systems. For example, due to difference between the center line of the optical system of a television camera tube and the axis of the electron beam generator which supplies the scanning beam, an effect known as the "keystone" effect occurs and this effect may be overcome by causing the amplitude of the horizontal deflection of the beam to vary in accordance with the amount of vertical deflection. This may be accomplished by amplifying the signal for producing horizontal deflection in a variable gain amplifier, the gain of which is determined by a second signal derived from the vertical deflecting system. In this instance it is desirable to have the amplitude of the signal E_1 substantially directly proportional to a constant plus the signal E_2 . This may be accomplished by using for V_1 and V_2 , tubes having the mutual conductance characteristic M shown in Fig. 2. If, for example, the signal E_2 varies the operating points of the tubes V_1 and V_2 from the grid voltage value GV_1 in Fig. 2 to the value GV_2 , the amplification or gain of the amplified signal E_1 will vary from g_{m1} to g_{m2} since the stage gain is substantially proportional to the mutual conductance of the tube.

In another instance it may be desirable to have the gain constant at one value part of the time, and zero or some low value other times. This may be done by using for V_1 and V_2 , tubes having a mutual conductance characteristic such as N in Fig. 2. In this case the control signal E_2 may vary the operating point from GV_4 to GV_3 for which points the gain will be zero and proportional to g_{m3} , respectively. It will be noted that if the gain curve N is flat topped from 17 to 18, the voltage of the control signal plus the input signal E_1 may be anywhere in the interval 17 to 18, thus permitting the use of larger input signals E_1 . Where a push-pull input circuit such as that of Fig. 4 is used, distortion of the signal E_1 due to the slope of the g_m curve is largely balanced out, and larger input signals may be employed. Tubes having characteristics as shown in Fig. 2 are now available commercially. For example, tubes of the type known as "42" have a characteristic similar to M while tubes of the type known as "47" have a characteristic similar to N . Other tubes having similar or different characteristics may, of course, be used, depending upon the particular application.

In Fig. 3, there is shown in block diagram a schematic outline of a circuit which may be used to avoid the keystone effect above mentioned. In the figure, horizontal and vertical deflecting signals E_h and E_v respectively are supplied to blocking tube oscillators 1 and 2 which in turn energize generators 3 and 4 which form the proper scanning signals. In the vertical signal circuit, the blocking tube oscillator 4 also energizes a sawtooth signal generator 5. The output of the generator 5 is supplied to a variable gain amplifier 6 of the type shown in Figs. 1 or 4 which amplifier is included in the horizontal signal circuit and serves to control the amplitude of the horizontal scanning signal in accordance with the vertical scanning signal, by which the keystone effect is eliminated. Both scanning signals are then amplified by power amplifiers 7 and 8 and used to energize appropriate deflecting

units 3 and 10, such as those commonly associated with cathode ray tubes.

From the illustrated embodiments and the above description, it will be seen that the invention provides novel means for the accomplishment of the objects and functions herein set forth. It will be understood, of course, that the present disclosure is merely illustrative and imposes no limitation upon the invention, the scope 10 of which is defined in the appended claims.

I claim:

1. In an electrical system, a plurality of space discharge devices each having an input circuit, an output circuit, and an effective mutual conductance, the mutual conductance of each of said space discharge devices being dependent upon the voltage in the input circuit of the respective discharge device, another space discharge device having an input circuit and an output circuit, an 15 impedance having a voltage thereacross in said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means for deriving signals from the output circuits of said plurality of space discharge 20 devices and for combining said derived signals in opposed relation to form an output signal.

2. In an electrical system, a plurality of space discharge devices each having an input circuit, an output circuit, and an effective mutual conductance, the mutual conductance of each of said space discharge devices being dependent upon the voltage in the input circuit of the respective discharge device, said discharge devices having similar electrical properties, another space 25 discharge device having an input circuit and an output circuit, an impedance having a voltage thereacross in said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means for deriving signals from the output circuits of said plurality of space discharge devices and for combining said derived signals in opposed relation to form an output signal.

3. In an electrical system, a plurality of space discharge devices each having an input circuit, an output circuit and an effective mutual conductance, the mutual conductance of each of said space discharge devices being dependent upon the voltage in the input circuit of the respective discharge device, another space discharge device having an input circuit and an output circuit, an impedance having a voltage thereacross in said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means for including an impedance in at least one of said output circuits for deriving signals from the output circuits of said plurality of space discharge devices and for combining said derived signals in opposed relation to form an output signal.

4. In an electrical system, a plurality of space discharge devices each having an input circuit, an output circuit and an effective mutual conductance, the mutual conductance of each of said space discharge devices being dependent upon the voltage in the input circuit of the respective discharge device, another space discharge device having an input circuit and an output circuit, an impedance having a voltage thereacross in said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means including an impedance in each of said output circuits for deriving signals from the output circuits of said plurality of space discharge devices and for combining said derived signals in opposed relation to form an output signal.

5. In an electrical system, a plurality of space discharge devices each having an input circuit, an output circuit and an effective mutual conductance, the mutual conductance of each of said space discharge devices being dependent upon the voltage in the input circuit of the respective discharge device, said discharge devices having similar electrical properties, another space 25 discharge device having an input circuit and an output circuit, an impedance having a voltage thereacross in said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means including an impedance in each of said output circuits for deriving signals from the output circuits of said plurality of space discharge devices and for combining said derived signals in opposed relation to form an output signal.

6. In an electrical system, a plurality of space discharge devices for providing signal channels, each having an input circuit, an output circuit and an effective mutual conductance, the mutual conductance of each of said space discharge devices being dependent upon the voltage in the input circuit of the respective discharge device, said discharge devices having similar electrical properties, another space discharge device having an input circuit and an output circuit, an impedance having a voltage thereacross connected to said input circuits and said output circuits, for establishing said voltage in each of said input circuits and each of said output circuits, means for introducing an input signal in the input circuit of at least one of said plurality of space discharge devices, means for introducing an input signal in the input circuit of said other space discharge device, and means including an impedance in at least one of said output circuits for deriving signals from the output circuits of said plurality of space discharge devices and for combining said derived signals in opposed relation to form an output signal, and means associated with at least one of said plurality of space discharge devices for balancing the frequency characteristic of the said output signal channels.

7. In an electrical system, a plurality of space discharge devices each having an input circuit, an output circuit, and an effective mutual con-

ductance, the mutual conductance of each of said space discharge devices being dependent upon the voltage in the input circuit of the respective discharge device, another space discharge device having an input circuit and an output circuit, an impedance having a voltage thereacross in said input circuits and said output circuits, for establishing said voltage in each of said input circuits and each of said output circuits, means for introducing an input signal in the input circuit of one of said plurality of space discharge devices

and for introducing an input signal of opposite phase relation in the input circuit of another of said plurality of space discharge devices, means for introducing an input signal in the input circuit of said other space discharge device, and means for deriving signals from the output circuits of said plurality of space discharge devices and for combining said derived signals in opposed relation to form an output signal. 5

PHILIP J. KONKLE. 10
